LEE S. CHADWICK, OF EAST CLEVELAND, OHIO, ASSIGNOR TO THE CLEVELAND METAL PRODUCTS COMPANY, OF CLEVELAND, OHIO, A CORPORATION OF OHIO.

OIL-STOVE.

1,274,989.

Specification of Letters Patent.

Patented Aug. 6, 1918.

Application filed August 8, 1914. Serial No. 855,860.

To all whom it may concern:

Be it known that I, LEE S. CHADWICK, a citizen of the United States, residing at East Cleveland, in the county of Cuyahoga and State of Ohio, have invented a certain new and useful Improvement in Oil-Stoves, of which the following is a full, clear, and exact description, reference being had to the accompanying drawings.

10 This invention relates to oil burners, and more particularly to burners of this type which are adapted to produce a flame suitable for use in a cooking stove. The various embodiments of the invention include a wick as the means whereby the oil is fed to the vaporizing point and whereby a vapor-evolving surface is provided. The various forms of the invention shown herein also relate to burners of the type wherein a blue 15 flame is produced through the manner of supplying air to the vapors evolved from the upper and exposed end of the wick and wherein, for this purpose, a centrally arranged air distributor or controller is provided within the upper end of the inner wick tube and a coöperating air distributor is provided outside of the outer wick tube and between the same and the surrounding drum, an instance of such burners being 20 shown in the patent to Hoffman No. 1,092,262, issued April 7, 1914.

It is the general object of this invention to improve the operation of burners of this type and particularly in the matter of safety, rendering the same practically immune from the dangerous conditions arising from the discharge of vapors about the lower ends of the wick tubes. These vapors, catching fire, will generate vapors from the 25 wick tubes in such quantity as to be incapable of proper combustion and control, while the heat produced by the combustion of the vapors about the bottoms of the wick tubes will break the connections in the oil supply to the wick tubes, whereby the oil may be ignited at the points where such breaks occur and the compartment in which the stove is located and the life of the operator be endangered thereby. With the foregoing 30 general object in view, the invention may

be defined further as consisting of the combinations of elements embodied in the claims hereto annexed and illustrated in the drawings forming part hereof, wherein Figure 1 represents a vertical sectional view of a 55 burner constructed in accordance with my invention, including the lower portion of the drum or chimney; Fig. 2 is a transverse sectional view, with parts broken away, corresponding to the line 2—2 of Fig. 1; Figs. 60 3, 4, 5, and 6 are vertical sectional views of modifications of the burner shown in Figs. 1 and 2.

Describing by reference characters the various parts illustrated herein and with 65 particular reference to Figs. 1 and 2, 1 denotes the inner and 2 the outer wick tube of the burner, 3 a lateral supply connection projecting from the bottom of the outer wick tube and 4 a hook which is secured to the inner wick tube, said connection and hook forming means whereby the burner may be connected to and the space between the wick tubes be placed in communication with the supply pipe (not shown) in the 70 manner described in patent to Jeavons No. 951,612 dated March 8, 1910. 5 denotes the wick which is mounted within the space between the wick tubes, said wick being provided with a carrier 6 which is adapted to 75 be engaged and operated by a wick raising wheel 7. The upper end of the inner wick tube is preferably bent or deflected outwardly, as shown at 1^a, while the upper end of the outer wick tube is bent inwardly, as 80 shown at 2^a, and then upwardly, as shown at 2^b, and the top of the inner wick tube preferably projects a short distance above the top of the outer wick tube.

8 denotes a narrow annular plate which 90 is carried by and projects inwardly from the inner wick tube, this annular plate or ring forming a seat for the air distributor which is within the top of the inner wick tube. This distributor comprises a body 95 (preferably hollow) which is mounted within the upper portion of the inner wick tube, said body being preferably in the shape of two cone frustums placed base to base and supported on the ring, whereby the lower 100

portion of the body forms with the top of the inner wick tube a passageway of diminishing cross sectional area from bottom to top, the upper portion of the distributor 5 projecting inwardly from a point preferably slightly above the top of the inner wick tube. This distributor, indicated generally at 9, is provided with a bottom 10, an inverted frusto-conical wall 11, and a frusto-conical wall 12 projecting upwardly from the last mentioned wall. The wall 11 is provided with a suitable number of outwardly projecting supporting devices, shown as plates 13 (four being shown), the lower ends 15 whereof are adapted to rest upon the ring 8, the plates being preferably of such extent as to be in substantial engagement with the inner wick tube, whereby the distributor may be centered. It will be observed that 20 the passageway formed between the bottom portion of the distributor 9 and the inner wick tube is one which is of uniformly diminishing cross sectional area as far as the top portion 1^a of the wick tube and that, 25 from the bottom of this portion 1^a, the diminution in cross sectional area of the passageway, while uniform, is not so marked as in the lower portion thereof. It will be observed also that the plane of greatest width 30 of the distributor 9 is slightly below the top of the wick, when the wick is in position for normal operation.

The outer wick tube is shown as provided with an outwardly projecting ledge 14, 35 which may conveniently be provided by doubling the metal thereof upon itself. On the seat thus formed is supported the chimney or drum and the parts which coöperate to distribute air to the exterior of the wick 40 and the exterior of the flame. 15 denotes a vertical ring or collar which surrounds the upper portion of the wick tube. The bottom of this collar is shown as supported by the ledge 14 and the collar is cylindrical 45 in contour as far as the top of the outer wick tube, where it is flared outwardly, as shown at 16. The bottom of the collar preferably fits the outer wick tube closely, the portion of the collar which is opposite the parts 2^a and 2^b of the outer wick tube forming therewith a trough or channel 2^c. The part of the collar forming the outer wall for this channel or trough is provided with a limited number of perforations 15^a through 50 which air may enter the channel and, sweeping upwardly, carry with it into the flame above any vapors that may drop into the channel from the vapor generating portion of the wick thereabove. The flange 16 is 55 also provided with perforations 16^a, which perforations admit air in like manner and for like purpose to the space immediately surrounding the outer exposed surface of the wick.

60 65 The ring or collar 15 is preferably pro-

vided with a downwardly and outwardly flaring imperforate bottom 17, which may be formed from the same sheet of metal as the ring or collar proper. This bottom is preferably imperforate and at its outer edge is 70 bent around the bottom flange 18 of the next element of the outer air distributor, this element being preferably made of sheet metal which is bent or suitably formed so as to provide a frusto-conical portion 19 extending 75 upwardly from the flange 18, a cylindrical portion 20 above the frusto-conical portion, an inwardly projecting flange 21, an upwardly projecting cylindrical portion 22, the last mentioned portion extending above 80 the top of the wick and the flange 16, being there bent inwardly and downwardly with its extreme inner edge 23 overhanging the top of the wick 5 and preferably located slightly outside the inner edge of such wick. 85 With the burner operating in normal condition, there will be a slight space (about $\frac{3}{2}$ to $\frac{1}{8}$ inch) between the top of the flange and the wick. In the frusto-conical portion 19 of the second air distributing element, a 90 suitable number of large openings 19^a will be provided, two horizontal series of such openings being shown. In the lower portion of the cylindrical part 22 of this element a series of large perforations 22^a will be provided, said perforations being located below the flange 16. It will be evident that the first and second elements form in effect a unitary structure, both of which are supported by the ledge 14, and that a chamber 100 is provided thereby which extends about the upper end of the outer wick tube.

The third element of the external air distributor comprises a cylindrical body 24 (preferably of sheet metal) which is of a 105 diameter to enable it to be slipped over the cylindrical portion 20 of the second distributing element and to enable the body to be supported in engagement with the frusto-conical portion 19 of the second element. At 110 its bottom, the third element is provided with an outwardly projecting flange 25. The upper end of the third element is extended upwardly and inwardly and is preferably curved to present a convex upper 115 surface as shown at 26. The convex upper end of the third element extends inwardly above the top of the second element with its inner edge 27 preferably in vertical alignment with the inner edge 23 of the element 120 therebeneath. The downwardly and inwardly projecting portion of this third element is provided with perforations, as shown at 26^a. The third element provides a passageway with the second element for conducting vapors and air into the space above the wick.

The chimney or drum 28 is preferably cylindrical and of the type shown in Jeavons Patent No. 1,038,590 issued Sept. 17, 1912, 125

and is preferably provided with an inverted frusto-conical bottom 29, the lower end whereof may be formed into a wire, as shown at 30, the inner diameter of the wired portion being such as to fit more or less closely about the cylindrical portion 24 of the third air distributing element, the drum being supported by the flange or ledge 25. The inclined or inverted frusto-conical portion of the drum is provided with perforations 29^a.

With the parts constructed and arranged as described, the operation will be as follows: The wick being turned up to about the position shown in Fig. 1 and ignited, vapor will be generated from the exposed top portion of the wick. Owing to the manner of supplying and distributing air, the flame, when the wick is at normal height, will be a blue flame extending upwardly in the space between the top of the air distributor 9 and the inner edges 23 and 27 of the exteriorly arranged overhanging plates. When operating under ordinary conditions, there is liability that some vapor evolved from the outer surface of the wick will not be carried upwardly and will, in fact, fall downwardly about the upper end of the wick tube. Such vapors will accumulate within the trough 2^c and will be carried thence upwardly into the flame by air admitted through the openings 15^a and 16^a.

In a burner constructed as shown herein, the particular arrangement of the inner and outer distributors will secure an efficiency which is greater than that of any other burner of the particular type illustrated herein with which I am familiar. In operation, however, the wick may be turned so high as to impinge against the lower edge 23 of the inwardly extending distributor flange thereabove, or it may be brought into undue proximity thereto. The flow of vapors from the major generating portion of the wick will then be entirely cut off or materially checked, as the case may be. In either event, vapors evolved from the outer portion of the wick will fall by gravity. In all other burners of the particular type shown herein with which I am familiar, these vapors will drop into close proximity to the outer wick tube and, being ignited there, will evolve vapors from the wick tubes in such quantity as will produce a flame which will not only be intensely smoky but will be incapable of control. Furthermore, the continued burning of vapors at this point will loosen or break the connections between the supply pipe and the burner, with attendant danger of conflagration. By the construction illustrated herein, should the operator happen to turn the wick too high, the vapors evolved from the outer exposed surface of the wick will fall into the surrounding chamber and then be caught

by the air flowing through the openings 19^a and swept through the openings 22^a into the passageway between the second and third elements of the external distributor and be discharged above the top of the wick and into the flame. As a further precaution against any inconsiderable quantity of vapors which might pass out through the openings 19^a (the bottom wall 17 being imperforate) these vapors will be caught by the air flowing upwardly through the openings 29^a and will be carried into the drum and above the flame therein. Finally, should any vapors thus liberated from the external surface of the wick fail to be taken care of through the two passageways provided therefor, the flange 17 will discharge these vapors at a point sufficiently remote from the wick tubes to prevent the undesirable consequences referred to hereinbefore, even if the vapors should be discharged in a sufficient quantity to produce a flame of any material extent—a remote contingency.

In Fig. 3 there is shown a modification of the invention illustrated in the preceding figures wherein the parts which are identical or substantially identical with those in the preceding figures are given like reference numerals. The inner and outer tubes, the ring 8, and the bottom part of the inner air distributor are identical in construction with the like numbered parts in the preceding views. The upper part of the inner distributor, instead of being frusto-conical, is shown as outwardly concaved, as shown at 12^a. The collar or ring 15 is omitted in this modification, and an outwardly and downwardly directed annular plate 17^a is mounted upon the outer wick tube and extends therearound in about the same manner as the plate 17 shown in Fig. 1. The outer portion of the plate 17^a is provided with a vertical flange 17^b and with a horizontal flange 17^c therebeneath, the flanges forming a seat for the lower wired end of an external distributor element which is similar to the element comprising the parts 19 to 23 in the preceding view. In this case, the external distributing element comprises a cylindrical lower portion 31 which may have a single series of large openings 32. The metal of this distributor element is shown as bent horizontally inwardly, at 33, and then upwardly in cylindrical form, at 34, the upper end being convex, as shown at 35, the extreme inner edge 36 of this convex portion being in the same position with reference to the wick therebeneath as the edge 23 of the corresponding element in the preceding modification. The cylindrical portion 34 is shown as provided with a series of large openings 34^a, corresponding to the openings 22^a in the preceding views. Outside of the distributing element just described is located another element corresponding to the ele-

1
ment 24—27 in the preceding figures. This element is shown as having a cylindrical portion 37, which is of a diameter to fit more or less closely upon the cylindrical portion 31 of the distributor element just described and to which it may be permanently secured, as by peening the overlapping portions of the metal together, as indicated at 38. The bottom of the cylindrical portion 37 is shown as formed into an outwardly projecting flange 39 and the top of the element is bent into convex form, as shown at 40, whereby it overhangs the corresponding part of the element therebeneath and forms therewith a passageway which diminishes in cross sectional area to the discharge outlet formed between the alined inner edges 41 and 36.

20 While the element 15 in the former views is missing from this modification, means are provided for forming a trough or channel about the upper exposed portion of the wick, such means consisting of an upwardly convex sheet metal member 42 which surrounds the exposed portion of the wick, said member being provided with a depending cylindrical flange 43 at its inner edge whereby it may be secured in any appropriate manner to the top of the outer wick tube. The portion of this member which projects upwardly and outwardly from the wick is provided with perforations 44 therein, through which a limited amount of air may be supplied to the channel formed between such portion and the wick.

35 The drum 28 is constructed in the same manner as in the preceding modification and has its lower end supported upon the flange 39.

40 The operation of the burner shown in Fig. 3 will be substantially the same as that shown in the preceding modification, it being noted that the upwardly convex part 40 of the outer air distributing mechanism is imperforate and that no trough or chamber 45 for vapor is provided with and below the top of the outer wick tube. In the construction described, however, should the wick be turned too high, air entering the openings 32 can sweep the vapors from the 50 chamber surrounding the upper end of the outer wick tube through the openings 34^a and through the passageway between the parts 35 and 40 into the central portion of the drum and above the wick tubes. Also, 55 should any vapors escape through the openings 32, they will be largely, if not entirely, caught up by the air flowing to and through the openings 29^a; and, should any vapors fall from the openings 32, they will be delivered at a sufficient distance from the burner parts to avoid danger of conflagration.

60 In Fig. 4 there is shown a further modification of the invention illustrated hereinbefore. In this view, the inner and outer

wick tubes are constructed in the same manner as heretofore described. The bottom of the inner air distributor and the manner of supporting the distributor are the same as those heretofore described. The upper end 70 of the distributor is outwardly concave, but the concavity is produced by two reversely extending conical surfaces 12^b and 12^c.

75 In this modification, no provision is made for admitting a limited quantity of air to a trough or chamber immediately surrounding the outer exposed portion of the wick and the top of the outer wick tube. A substantially horizontal annular plate 17^a is shown as carried by the upper portion of 80 the wick tube in substantially the same manner as the plate 17^a, and its outer edge is shown as bent around a horizontal flange 45 projecting from the bottom of an air distributing element which may comprise 85 said flange, a vertical cylindrical portion 46 above said flange, a frusto-conical portion 47 above the cylindrical portion, a downwardly inclined portion 48, and a cylindrical portion 49. The parts 45 to 49 90 may conveniently be made of a single sheet of metal and the cylindrical part 49 of this element is adapted to be fitted to the top of the outer wick tube in the same manner as is the cylindrical portion 43 of the element 95 42—44 in Fig. 3. It will be evident that the upwardly and outwardly extending portion 48 will provide an imperforate trough or chamber surrounding the outer exposed portion of the wick and that the portion 47 of the plate will form an inclined bottom for the chamber thereabove. Mounted upon the flange 45 and preferably closely fitting the cylindrical portion 46 is a cylindrical sleeve 50. This sleeve is provided, above the 100 flange 46, with a series of large openings 51 extending therearound. Above these openings there is provided an air distributing element comprising preferably a sheet metal plate which may be bent so as to form a 110 short cylindrical skirt 52, an inwardly projecting flange 53 thereabove, a vertically extending flange or cylinder 54 and an upwardly convex inwardly extending top portion 55, the extreme inner edge 56 whereof 115 overhangs the inner portion of the wick therebeneath. The construction and arrangement of the parts 52 to 56 is substantially identical with that of the parts 20 to 23 in Fig. 1 and the cylindrical portion 120 54 is provided with a series of large openings 54^a extending therearound. The distributing element 52—56 is shown as secured permanently to the sleeve 50, as by "peening" the metal together (indicated at 57). 125 The element 52—56 forms with the sleeve 50 and the element 45—49 a chamber surrounding the upper end of the outer wick tube.

130 At its upper end, the skirt 50 supports an

air distributing element which may be formed from a plate of sheet metal, said plate being shown as bent to form an annular seat 58 at its outer edge for the drum 28^a, the plate being further bent to provide a horizontal ring 59 between the drum seat and the top of the sleeve, which horizontal ring is provided with a series of perforations 59^a. The distributor plate may then be bent downwardly, as shown at 60, to fit within the top of the sleeve 50, to which it may be secured, as by peening the metal together (see 61). The plate is then bent inwardly and downwardly above the part 55 of the distributing element therebeneath, forming therewith a passageway which diminishes in cross sectional area toward the inner or discharge end. This inwardly projecting portion is shown at 62, and the extreme inner edge 63 thereof is located above the inner edge 56 of the element therebeneath. The inwardly projecting portion of the last described element is provided with perforations, indicated at 62^a.

25 The operation of the burner disclosed in Fig. 4 will be substantially the same as that of the burner shown in the preceding views, except that no perforations are provided whereby air can enter the trough or chamber formed about the outer exposed portion of the wick. Should the wick be turned unduly high, any vapor evolved from the outer surface of the wick will be directed outwardly by the inclined wall 47 and will 30 practically all be caught by air entering the chamber through the openings 51 and be carried through the openings 54^a into the passageway between the plates 55 and 62 and be discharged mainly through the slot 35 between the edges 56 and 63 into the flame. Some of the vapors will be discharged 40 through the openings 62^a. It will be observed that, in this modification as well as in those shown in the preceding views, the bottoms of the openings through which the air may enter to conduct the vapors above the flame are located above the part therebeneath, whereby a space will be provided in which the vapors may collect before they 45 50 may overflow through such openings. Any vapor that may overflow through the openings, will be practically entirely caught by the draft passing upwardly through the openings 59^a, and any that may not be carried through either of the separate paths 55 thus provided, will be discharged at a sufficient distance from the burner to avoid danger, even should they be present in a quantity sufficient otherwise to cause such 60 danger.

In Fig. 5, there is shown a still further modification of the invention, wherein the inner and outer wick tubes and the inner air distributor are identical in construction 65 with the like-designated parts in Fig. 3.

The external distributing member immediately surrounding the top of the outer wick tube is practically identical with that shown in Fig. 4 and is numbered in like manner. The outer horizontal flange 45 of this member is engaged by the outer edge of an upwardly inclined plate 17^a, the lower end of which is secured to the wick tube in any approved manner. The outwardly projecting flange 45 and the cylindrical portion 46 70 coöperate to center and support thereupon a sleeve which is substantially identical with the sleeve 50 in the preceding figure, which sleeve and its component parts will be numbered in like manner as in the preceding figure. At its upper end, the sleeve is secured to a cylindrical portion of an air distributor member which is similar to the member 58—63 in Fig. 4. This distributor member is preferably made from a sheet 75 metal plate and has its outer edge provided with an upwardly projecting cylindrical seat 64 for the bottom of the drum 28^b. The plate is then shown as bent inwardly, at 65, to form a horizontal ring having perforations 65^a therethrough. Thence it is shown as bent downwardly to form a cylindrical flange 66 to which the upper end of the sleeve 50 may be secured, as by peening (see 66^a). From the bottom of the cylindrical part, the distributor plate is shown as projected inwardly and downwardly, at 67, being of substantially the same shape as the part 62 in the preceding modification. The distributing element or member intermediate 80 of the one just described and the one comprising the parts 45—49 is shown as secured to the plate 67. This intermediate distributing element comprises preferably a sheet metal plate which may be bent to form 85 a horizontal flange 69 by which the element may be secured to the element 67, thence may be bent downwardly to form a cylindrical portion 70 having large perforations 70^a 90 therein. Thence the plate extends inwardly and horizontally, as shown at 71, and at its inner end is upwardly convex, as shown at 72, the extreme inner edge 73 being arranged in the same relation to the top of the wick therebeneath and to the edge 68 of the element thereabove as is the case with the corresponding elements in the preceding modification. The operation of this burner will be substantially the same as that in the preceding modification. Any vapor dropping 95 from the outside of the wick (as through the undue elevation of the wick) will flow down the frusto-conical portion 47 of the chamber about the upper end of the outer wick tube, but will practically entirely be caught by 100 the air entering the perforations 51 and be conveyed through the openings 70^a into the passageway between the plates 67 and 71 and be discharged between the edges 73 and 105 68 of said plates. For any vapors which 110

may pass outwardly through the openings 51 a path is provided through the openings 65^a. Any vapors which may happen to escape either of these two paths will be delivered outwardly and away from the burner tubes and in such inconsiderable quantity as to avoid danger.

In Fig. 6 there is shown a still further modification of my invention wherein the 10 inner and outer tubes, the inner air distributing element, the member comprising the parts 45-49, the members, 17^a, the cylindrical sleeve 50, the drum 28^b and the air distributing member comprising the parts 15 64-68 are identical with the like numbered parts in the preceding figure, the only difference in construction being that the intermediate external air distributing element, instead of being carried by the element 20 64-68, is carried by the sleeve 50. This intermediate member is preferably formed of a plate of sheet metal and is shown as having its outer end formed into a cylindrical flange 74 by which it may be secured to 25 the sleeve 50, as by means of peening (see 74^a). The body of the plate then projects inwardly, as shown at 75, and has its inner portion upwardly convex, as shown at 76, the extreme inner edge 77 occupying the 30 same relation with reference to the top of the wick and the inner edge 68 of the distributor member thereabove as is the case with the corresponding part in the preceding views. The sleeve 50 is provided with 35 a series of perforations 50^a communicating with the space between the upper and the intermediate air distributing elements.

The operation of the burner shown in the last described figure will be identical with 40 the operation of that shown in the preceding figure except that any vapor which may flow down the inclined wall 47 of the chamber surrounding the upper end of the outer wick tube will accumulate above the openings 51 until it can flow therethrough, when 45 it will be caught by the upward draft of air and be carried through the openings 50^a and 55 and be discharged into the flame and through the openings 65^a into the drum. Should any considerable quantity of vapors fail to be thus disposed of, they will be conducted away from parts which might be endangered through their combustion.

55 Having thus described my invention, what I claim is:

1. In a burner of the character described, the combination of an inner and an outer wick tube, a wick therebetween, an air distributor within the upper portion of the inner wick tube, and an air distributor about the upper portion of the outer wick tube, the last mentioned distributor having a chamber surrounding and extending below 60 the top of the outer wick tube and having 65

a flange extending above the top of the wick, there being a passageway above said chamber arranged to conduct above the flange and into the space above the wick any fluids that may be in the chamber, one wall 70 of said chamber being provided with openings communicating with said passageway and with openings beneath the first mentioned openings adapted to admit air into the chamber and to permit the escape of 75 vapor from the chamber, the bottom wall of the chamber being formed to constitute a deflector for directing away from the wick tubes and toward the second mentioned openings vapor passing downward through 80 the chamber.

2. In a burner of the character described, the combination of an inner and an outer wick tube, a wick therebetween, an air distributor within the upper portion of the 85 inner wick tube, an air distributor about the upper portion of the outer wick tube, the last mentioned distributor comprising a chamber having a closed bottom projecting outwardly from the outer wick tube, the 90 outer wall of said chamber having a flange projecting inwardly above the wick and said wall having, above the bottom, openings for admitting air to the chamber and said chamber having in its outer wall openings above 95 the last mentioned openings, and a passageway located about the upper portion of the chamber and arranged to conduct fluids into the space above the wick, the passageway communicating with the chamber through 100 the second set of openings.

3. In a burner of the character described, the combination of an inner and an outer wick tube, a wick therebetween, an air distributor within the upper portion of the 105 inner wick tube, and an air distributor about the upper portion of the outer wick tube, the last mentioned distributor comprising a chamber extending about the upper end of the wick tube and adapted to receive therewithin any vapors that may fall from the outer exposed portion of the wick, said chamber having a bottom wall extending outwardly from the wick tube and an outer wall extending upwardly from the bottom 110 wall and provided with a flange projecting inwardly and above the wick, said outer wall having a series of openings above the bottom wall and a second series of openings above the first mentioned series, there being 115 a passageway about the part of the outer chamber wall containing the second series of openings, said passageway being arranged to discharge into the space above the wick whereby vapors that may fall from the outer 120 exposed portion of the wick will be intercepted by air flowing upwardly through the lower series of openings in the chamber and conducted through the upper series into and through the passageway and whereby any 125 130

vapors not conducted above the wick tubes will be discharged outwardly by the bottom wall at a point remote from the wick tubes.

70

4. In a burner of the character described, 5 the combination of an inner and an outer wick tube, a wick therebetween, an air distributor within the upper portion of the inner wick tube, and an air distributor about the upper portion of the outer wick tube, 10 the last mentioned distributor comprising a chamber extending about the upper end of the wick tube and adapted to receive therewithin any vapors that may fall from the outer exposed portion of the wick, said 15 chamber having a bottom wall extending outwardly from the wick tube and an outer wall extending upwardly from the bottom wall and provided with a flange projecting inwardly and above the wick, said outer 20 wall having a series of openings above the bottom wall through which air may be admitted to the chamber or vapor may escape therethrough when conducted to the vicinity of said openings by the bottom wall, and a 25 second series of openings above the first mentioned series, there being a passageway surrounding the part of the outer chamber wall containing the second series of openings, said passageway being arranged to discharge 30 into the space above the wick whereby vapors that may fall from the outer exposed portion of the wick may be intercepted by air flowing upwardly through the lower series of openings in the chamber and 35 through the upper series into and through the passageway, vapors not thus intercepted and not directed outwardly by the bottom wall at a point remote from the wick tubes being conducted above the wick tubes by the 40 upper portion of the outer wall of the chamber and the aforesaid flange which projects inwardly from the upper end of such wall.
5. In a burner of the character described, 45 the combination of an inner and an outer wick tube, a wick therebetween, an air distributor within the upper portion of the inner wick tube, and an air distributor about the upper portion of the outer wick tube, the last mentioned distributor comprising a 50 chamber surrounding the upper portion of the outer wick tube and adapted to receive therewithin any vapors that may be disengaged from the outer exposed surface of the wick, said chamber having a bottom wall 55 which is inclined downwardly and outwardly from the outer wick tube and a wall extending upwardly from the bottom wall and having a flange projecting inwardly above the top of the wick, the outer 60 wall being provided with openings above the bottom wall and there being a passageway extending above the said flange to the space above the wick, said passageway communicating with said chamber whereby air 65 entering the chamber through the openings

above the bottom plate may pass through the lower portion of the chamber and through the passageway and carry therewith vapors which may accumulate within the chamber.

75

6. In a burner of the character described, the combination of an inner and an outer wick tube, a wick therebetween an air distributor within the upper end of the inner wick tube and an air distributor about 75 the upper portion of the outer wick tube, the last mentioned distributor comprising a flange extending upwardly and outwardly from the top of the outer wick tube, a chamber located outside of said flange and 80 extending above and below the same, said chamber having an outwardly extending bottom wall and having openings in its side wall above said bottom wall, said chamber also having an inwardly projecting flange 85 extending above the wick, the exterior distributor also comprising a passageway extending above the flange and arranged to discharge at a point above the wick, said passageway communicating with the chamber. 90

95

7. In a burner of the character described, the combination of an inner and an outer wick tube, a wick therebetween, and an air distributor within the upper portion of the inner wick tube, and an air distributor about the upper portion of the outer wick tube, said distributor comprising a chamber which is arranged to receive therewithin any vapors that may fall from 100 the outer exposed portion of the wick and direct such vapors into the space above the wick, the chamber having a wall which directs vapors that may not be so conducted to the space above the wick to a point remote 105 from the wick tubes, said wall serving to positively prevent the escape of such vapors adjacent said tubes.

105

8. In a burner of the character described, the combination of an inner and an outer wick tube, a wick therebetween, an air distributor within the upper portion of the inner wick tube, and an air distributor about the upper portion of the outer wick tube, said distributor comprising two passageways and a chamber, the chamber being arranged to receive through one of said passageways any vapors that may fall from the outer exposed portion of the wick, the passageways serving to conduct such vapors into the space above the wick, the chamber having a bottom wall which directs vapors that may not be so conducted to the space above the wick to a point remote from the wick tubes. 115

115

120

125

9. In a burner of the character described, the combination of an inner and an outer wick tube, a wick therebetween, an air distributor within the upper portion of the inner wick tube, and an air distributor 130

about the upper portion of the outer wick tube, said distributor comprising a chamber extending around the outer wick tube and having a flange projecting inwardly above the top of the wick and adapted to receive therewithin the vapors falling from the outer exposed surface of the wick, said chamber having an outwardly extending bottom wall and a side wall that is provided 5 with perforations above said bottom wall, said exterior distributor also comprising a passageway extending inwardly above the flange and arranged to discharge into the space above the wick, there being means for 10 admitting vapors accumulating within the chamber into the passageway.

10. In a burner of the character described the combination of an inner and an outer wick tube, a wick therebetween, an air distributor within the upper portion of the inner wick tube, and an air distributor extending about the upper portion of the outer wick tube, the last mentioned distributor comprising two passageways and a 15 chamber located therebeneath, the chamber being adapted to receive through one of said passageways any vapors which may be discharged from the outer exposed surface of the wick, the passageways serving to conduct such vapors into the space above the wick, the chamber having an air inlet 20 through which air may be admitted to carry the vapors which may accumulate within the chamber through said passageways.

35. 11. In a burner of the character described, the combination of an inner and an outer wick tube, a wick therebetween, an air distributor within the upper portion of the inner wick tube, and an air distributor about 40 the upper portion of the outer wick tube, the last mentioned distributor comprising a casing inclosing a chamber surrounding the upper portion of the outer wick tube and adapted to receive therewithin any vapors 45 that may fall from the outer exposed surface of the wick, said casing involving an inwardly directed flange extending above the wick and forming a passageway thereabove, the casing having openings through 50 which the passageway and chamber communicate, and further openings through which air may be admitted to the chamber or vapors may escape therefrom, and a drum 55 above the wick tubes, said drum having an inlet in the vicinity of the last mentioned openings of the casing.

12. In a burner of the character described, the combination of an inner and an outer wick tube, a wick therebetween, an air distributor within the upper portion of the inner wick tube, an air distributor extending about the upper portion of the outer wick tube, the last mentioned distributor comprising a chamber extending about the upper 65 portion of the outer wick tube and adapted

to receive therewithin any vapors that may fall from the outer exposed surface of the wick, said chamber having an inwardly directed flange extending above the wick and such exterior distributor comprising a passageway above the flange, means for conducting vapors which may accumulate within the chamber into said passageway, the chamber having a bottom wall and a side wall that is provided with an opening above 70 said bottom wall, a drum, and a perforated ring for the bottom of the drum which reposes above the opening of the side walls.

13. In a burner of the character described, the combination of an inner and an outer wick tube, a wick therebetween, an air distributor within the upper portion of the inner wick tube, and an air distributor extending about the upper portion of the outer wick tube, said distributor comprising a 85 chamber having a bottom plate extending outwardly from the wick tube and said chamber being adapted to receive therewithin vapors which may fall from the outer exposed surface of the wick, said chamber being provided with openings in its side wall above said plate and having a flange extending inwardly above the top of the wick, there being a passageway formed with and above 90 said flange and communicating with the chamber through openings in a wall thereof, said passageway being adapted to receive vapor from the chamber and conduct the same inwardly to a point above the wick, a perforated ring projecting outwardly from 95 the exterior distributor above the openings in the side wall of the chamber, and a drum extending upwardly from the outer portion of said ring.

14. In a burner of the character described, the combination of an inner and an outer wick tube, a wick therebetween, an air distributor within the upper portion of the inner wick tube, and an air distributor extending about the upper portion of the outer 110 wick tube, said distributor comprising a casing having a bottom wall extending outwardly from the wick tube and being adapted to receive therewithin vapors which may fall from the outer exposed surface of the 115 wick, said casing being provided with openings above said wall and involving a flange extending inwardly above the top of the wick, there being a passageway formed above 120 said flange and a chamber below, the passageway being in communication with and adapted to receive vapor from the chamber and conduct the same inwardly to a point above the wick, and a drum extending above the wick tubes, the drum having an inlet in 125 the vicinity of the openings of the casing.

15. In a burner of the character described, the combination of an inner and an outer wick tube, a wick therebetween, an air distributor within the upper portion of the in- 130

ner wick tube, and an air distributer surrounding the upper portion of the outer wick tube, said distributer comprising a casing which is adapted to receive therewithin 5 vapors falling from the outer exposed surface of the wick, a drum extending about and above the outer distributer casing, the casing involving a flange whereby it is divided into a passageway and chamber, said 10 flange having an opening through which the passageway is adapted to receive vapors from the chamber, the passageway being of such shape as to conduct the vapors above the wick, the casing having an opening 15 through which air may be admitted to the chamber and vapors may escape therefrom, the drum having an inlet in the vicinity of the opening of the casing, the exterior distributer being so constituted as to direct 20 vapors, which may not be conducted through the passageway, toward said opening of the casing.

16. In a burner of the character described, the combination of an inner and an outer 25 wick tube, a wick therewithin, an air distributer within the upper portion of the inner wick tube, and an air distributer extending about the upper portion of the outer wick tube, said distributer comprising a 30 chamber the inner wall whereof fits closely about the upper portion of the outer wick tube and forms with the upper end of said tube a trough, said wall being perforated to admit air in limited quantity to said trough 35 and said chamber having a bottom wall extending outwardly from the outer wick tube and having an outer wall extending upwardly from the outer portion of the bottom wall and provided above such bottom with a 40 series of openings, the upper portion of the outer wall being projected inwardly to form a flange extending above the top of the wick, and a wall coöperating with the outer wall of the chamber and extending inwardly 45 above the flange to form with such outer wall and the flange a passageway, there being openings placing the passageway in communication with the chamber, the inwardly projecting portion of the last mentioned wall 50 being perforated, and a drum or chimney surrounding the exterior air distributer, there being a perforated ring at the bottom of the drum, the said ring being located above the openings in the outer chamber 55 wall in position to receive any vapors that may be discharged from such openings and which may be carried upwardly by the draft of air through such ring.

17. In a burner of the character described, the combination of an inner and an outer wick tube, a wick therebetween, an air distributer within the upper portion of the inner 55 wick tube, and an air distributer extending about the upper portion of the outer wick tube, said distributer comprising a chamber the inner wall whereof fits closely about the upper portion of the outer wick tube and forms with the upper end of said tube a 60 trough and said chamber having a bottom wall extending outwardly from the outer wick tube and having an outer wall extending upwardly from the outer portion of the bottom wall and provided above such bot-

tom with a series of openings, the upper portion of the outer wall being projected inwardly to form a flange extending above the top of the wick, and a wall coöperating with the outer wall of the chamber and extending 70 inwardly above the flange to form with such outer wall and the flange a passageway, there being openings adapted to conduct vapors from the chamber to the passageway.

18. In a burner of the character described, 75 the combination of an inner and outer wick tube, a wick therebetween, an air distributer within the upper portion of the inner wick tube, and an air distributer extending about the upper portion of the outer wick tube, 80 said distributer comprising a chamber the inner wall whereof fits closely about the upper portion of the outer wick tube and forms with the upper end of said tube a trough, said wall being perforated to admit 85 air in limited quantity to said trough and said chamber having a bottom wall extending outwardly from the trough and an outer wall extending upwardly from the bottom wall and provided above such bottom with 90 a series of openings, the upper portion of the outer wall being projected inwardly to form a flange extending above the top of the wick, a wall coöperating with the outer wall of the chamber and extending inwardly above 95 the flange to form with such outer wall and the flange a passageway, there being openings placing the passageway in communication with the chamber, the inwardly projecting portion of the last mentioned wall 100 being perforated, and a drum or chimney surrounding the exterior air distributer, there being a perforated ring at the bottom of the drum, the said ring being located above the openings in the outer chamber 105 wall in position to receive any vapors that may be discharged from such openings and which may be carried upwardly by the draft of air through such ring.

19. In a burner of the character described, 110 the combination of an inner and an outer wick tube, a wick therebetween, an air distributer within the upper portion of the inner wick tube, and an air distributer extending about the upper portion of the outer wick tube, 115 said distributer comprising a chamber, the inner wall whereof fits closely about the upper portion of the outer wick tube and forms with the upper end of the wick a trough and said chamber having a 120 bottom wall extending outwardly from the trough and an outer wall projecting upwardly from the bottom wall and provided above such bottom with a series of openings, the upper portion of the outer wall being 125 projected inwardly to form a flange extending above the top of the wick, a wall coöperating with the outer wall of the chamber and extending inwardly above the flange to form with such outer wall and the flange 130

a passageway, there being openings placing the passageway in communication with the chamber, and a drum or chimney surrounding the exterior air distributer, there being 5 a perforated ring at the bottom of the drum, the said ring being located above the openings in the outer chamber wall in position to receive any vapors that may be discharged from such openings and which may 10 be carried upwardly by the draft of air in such ring.

20. In a burner of the character described, the combination of an inner and an outer wick tube, a wick therebetween, an air distributer extending about the upper portion 15 of the outer wick tube, and an air distributer within the upper portion of the inner wick tube, said air distributer comprising an inverted frusto-conical body the enlarged portion 20 whereof is substantially as high as the top of the inner wick tube and said distributer having an inwardly projecting portion above the enlarged portion, the top of the inner wick tube being deflected outwardly.

25. 21. In a burner of the character described, the combination of an inner and an outer wick tube, a wick therebetween, an air distributer extending about the top of the outer wick tube, the top of the inner wick 30 tube being deflected outwardly, and an air distributer within the upper portion of the inner wick tube and comprising an inverted frusto-conical lower portion having its top slightly above the top of the inner wick tube

and said distributer having a frusto-conical top portion extending upwardly from the enlarged portion of the body. 35

22. In a burner of the character described, the combination of an inner and an outer wick tube between which a wick is adapted 40 to be supported, an air distributer within the inner wick tube, a second air distributer comprising a member surrounding the upper portion of the outer wick tube, a second member overhanging the upper end of the 45 wick and having a depending, perforated portion which surrounds and is spaced radially from the first member, said portion being of increased diameter toward its lower end whereby a restricted passageway is 50 formed between the upper portions of the opposed walls of said first and second members, and a third member above the second member, the space between said second and third members receiving its supply of air 55 from the aforesaid restricted passageway, whereby the velocity of a current of air which passes upward through the second distributer is increased within the restricted passageway and acts to carry upward vapors that may drop from the wick. 60

In testimony whereof, I hereunto affix my signature in the presence of two witnesses.

LEE S. CHADWICK.
